UNITED STATES PATENT OFFICE

2,587,587

SUSPENSION INSULATOR FOR HIGH-TENSION CONDUCTORS

Russell G. Bellezza and George M. Ruoff, Baltimore, Md., assignors to General Electric Company, a corporation of New York

Application October 15, 1945, Serial No. 622,408

12 Claims. (Cl. 174—140)

1

The invention relates to insulators and more particularly to novel means for supporting high tension and distribution conductors.

The principal object of our invention, generally considered, is to so connect and arrange a plurality of insulator rods or tubes as to directly support high tension transmission or distribution lines therefrom.

Another object of our invention is to substitute for the usual string of suspension insulators a plurality of insulating rods, either hollow or solid, said rods being of a length substantially equal to a string of suspension insulators, said rods being individually connected at one end to a pole or support and extending laterally therefrom and having their opposite ends connected by convenient and suitable means, said means serving as a support for the conductor.

Another object of the invention is to provide a plurality of insulating rods of adequate strength and length, said rods being each connected at one end to a support and extending laterally therefrom and having their opposite ends joined by a member, the latter being connected to and supporting the conductor.

Still another object of the invention is to substitute for the strings of suspension insulator units and the rigid supporting members therefor a vertical support having pivotally connected thereto in spaced relation and extending laterally therefrom a plurality of insulating rods (either hollow or solid), said rods having their outer ends connected to form a supporting member and being of a length sufficient to provide an adequate air gap between a conductor and the ground.

Still another object of our invention is to provide, in connection with rods of the type described, a flexible connection for the adjacent rod end to thereby relieve one or more of the rods of stresses other than direct tension or compression.

A still further object of the invention is to provide, in connection with insulating rods of the type described, lightning arresters, fuses or like apparatus housed within the rods, if hollow, or attached to the rods, if solid, to thereby eliminate the usual complicated apparatus and mechanism heretofore used for this purpose in connection with strings of suspension insulators, thereby using the insulating rod or tube as both a conductor support and a housing or attachment member for a piece of apparatus.

Still another object of the invention is to provide, in connection with insulating rods of the type described, each of the rods having one end

2

pivotedly connected to a support, a connector for their adjacent ends and to support on this connector one or more insulators of the conventional type, the latter in turn supporting the conductor to thereby place the insulating rods in series with the conventional insulators and hence to reduce the number of conventional insulators necessary to support high tension conductors.

Still another object of the invention is to provide with insulating rods of the type described pivotal means supporting the spaced ends of the rods from the support, said means being so arranged that on the breaking of the conductor the rods will swing into a plane substantially parallel to the direction in which the unbroken portion of the conductor extends.

Still another object of the invention is to provide, in connection with insulating rods of the type described, pivotal means arranged in spaced relation on the support to which the adjacent ends of the rods are respectively connected, the pivotal means being so disposed as to cause the member connecting the outer ends of the individual rods to move upwardly from normal position (that is at right angles to the support) on a pivotal movement of the rods so that the assembly is thereby stabilized against undesired lateral motion.

Other objects of the invention will hereinafter appear in connection with the detailed description of the embodiments thereof illustrated in the accompanying drawings, in which:

Figure 1 is a side elevational view showing a support and pivotally mounted insulating rods supporting a conductor at their adjacent ends.

Figure 2 is likewise an elevational view of a slightly modified form employing three rods and a different form of supporting member.

Figure 3 is a side elevational view of the conductor supporting clamp illustrated in Figure 2.

Figures 4 and 5 are respectively side elevational views showing different arrangements of the insulating rods in reference to their support and in reference to the conductor, Figure 4 showing a pair of insulators in series with the insulating rods.

Figures 6 and 7 are views similar to Figure 5 illustrating the use of corrugated rods and both illustrating the use of one of the rods as a support for the distribution conductors.

Figures 8 and 9 are fragmentary cross sectional views showing the application of lightning arresters housed within one of the supporting tubes illustrated in the preceding figures.

Throughout the specification and drawings

similar parts are designated by like reference characters.

Referring now to the drawings, the numeral 1 designates a conventional pole by which the rod insulators 2 and 3 may be supported. It is to be understood that there is no limitation as to the character of support and that the illustration of a wooden pole is merely to be taken as indicative of any type of support.

Projecting laterally from one face of the pole 1 is a plurality of clevis members 4 and 5, the clevis being positioned with the slot 6 in a substantially horizontal position and it will be noted that the clevis 5 is of less length than the clevis 4 so that the pins 7 and 8, which respectively connect each clevis to the respective tongues 9 and 10 of the insulating rods 2 and 3, are out of vertical alinement, the arrangement being such that the outer ends of the pivotally connected rods 2 and 3 are swung in an ascending spiral path on either side of a normal position and thus always tend to maintain a position substantially at right angles to the direction of the conductor 11 which is supported at the outer ends of the rods 2 and 3, as hereinafter described.

Each rod is provided at its inner end with a cap member 12, the cap members being identical except for the extent of the tongues 9 and 10 which are of course interposed between the jaws of their respective clevis members and are pivotally connected thereto, as heretofore set forth, by the bolts 7 and 8. It will be obvious to those skilled in the art that we may substitute for the form of connection shown, a tongue extending from the support 1 and a clevis member extending from the caps 12. Each clevis is preferably connected to the support by means of bolts and nuts 13.

Preferably formed integral with the cap 14 secured to the outer end of the rod 2 is a member 15 in which is pivotally supported a saddle clamp 16 by means of which the conductor 11 is supported. The member 15 is provided beneath the cap 14 with a tongue 16a to which the clevis member 17 of the cap 18 on the rod 3 is preferably pivotally connected by means of the bolt 19.

The arrangement heretofore described is illustrated in Figure 1 and it will be readily apparent that the rods 2 and 3, their respective caps 12, 14 and 18, the member 15, and the saddle 16 will be assembled at the plant or factory and that after the cap 12 of the rod 2 is connected the rod 3 is pivotally moved in reference to the pivotal connection 19 so as to bring the tongue 10 thereof into registration with the opening for the bolt 8 by means of which the cap 12 of this rod is pivotally connected to the support.

Referring now to Figure 2, in which we have illustrated the use of three rods, rather than two, as previously described, the upper rod 2a is pivotally connected to the member 15a, formed on the outer cap 14a of the rod 2, by a pin 19 extending through the jaws of the clevis 18a formed on the cap 18 and likewise the rod 3 is pivotally connected through its cap 18 with the adjacent portion of the member 15a. The cap members 12 at the inner or support adjacent end of the rods are connected to the clevis members 4, 5 and 5a by the bolts, clearly shown, and each of the clevis members is connected to the support 1 by bolts and nuts 13.

We preferably support the conductor from the member 15a by means of a link 20, the detachable link 21 and the stirrup member or clamp 22. This stirrup member is provided with a keeper

23 which is maintained in position by a plurality of bolts and nuts 24, as is usual.

In Figures 4, 5, 6 and 7 the form of connection between the cap members 12 and the clevis members 4 and 5 is substantially identical with that illustrated and described in connection with Figure 1 and further description is believed to be unnecessary. Likewise, the clevis members are connected to the support 1 by bolts and nuts 13 also previously described.

It will be noted that in Figure 4 the upper rod 2, instead of extending horizontally, is arranged at an angle to the horizontal and the rod 3 extends substantially in a horizontal direction. The cap members 25 on the outer end of the rods 2 and 3 in each of the Figures 4 to 7, inclusive, are provided with extension members 26, one of which ends in a clevis 27 and the other in a tongue 28, and the members 26, and consequently the rods 2 and 3, have their outer ends connected by a bolt 29 which is also adapted to form a support either for the clamp member 23 or for the insulators 30, which in turn support the conductor clamp 23.

In Figures 5, 6 and 7 the upper rod 2 of Figure 5 and 2b of Figures 6 and 7 preferably extend in a substantially horizontal direction while the lower rod 3 of Figures 5 and 6 and 3a of Figure 7 are arranged at an angle to the horizontal. The rods 2b and 3a are preferably provided with a corrugated surface diagrammatically illustrated as at 31 in Figures 6 and 7 and supported between certain pairs of adjacent corrugations on the rods 2b are the distribution cables 32. Tie wires, not illustrated, are preferably employed to maintain the distribution cables in position.

In Figure 7 the rod 3a is likewise provided with a corrugated surface 31 corresponding to the corrugated surface of the rods 2b.

From an inspection of Figures 1, 2 and 4 to 7, inclusive, it will be seen that in each of these figures one of the insulating rods is in compression, while the other rod acts in tension and, by reason of the flexible connection at the outer end of the rods, they will have ample strength without excessive cross sectional area, to support a high tension transmission line conductor.

The flange 33 of the caps 12, 14, 18 and 25, 43 and 48 form an efficient guard to protect the insulating rods in the event of flash-over. The air gap distance between ground and the conductor is preferably as great as the usual air gap distance between the ground and conductor of a string of high tension insulators and, as shown in Figures 4, 6 and 7, additional insulator units may be employed in series with the insulating rods to more adequately protect the line against flash-over or lightning surge.

Referring now to Figures 8 and 9, we have illustrated two forms of lightning arrester. Figure 8 shows the fuse type of supporting tube, in which there is housed within the supporting tube 3b a fiber tube 34 which preferably extends the entire length of the tube 3b and within this fiber tube and connected to the cap member 25a is a conductor 35 and the cap member 12a is provided with an opening 36 through which the hot gases generated by a flash-over will be forced.

In Figure 9 we preferably insert into one end of a supporting tube 3b a plurality of ceramic disks 37 having their opposing faces coated with a conducting substance 38, the innermost disk 39 having a metallic conductor 40 connected thereto and the cap 12b is also provided with a conductor member 41 extending into the tube

and is further provided with an opening 36. In this type of arrester the lightning flash-over connects the conductors 40 and 41 but the power arc is blocked and prevented from continuing along the path of the flash-over.

The tubes 3b of Figures 8 and 9 are preferably externally corrugated similar to the tubes or rods 2b of Figure 7, so that if desired, the distribution conductors 32 may be readily secured thereto by the usual tie wires.

Having thus described our invention, what we claim as new and desire to secure by Letters Patent is:

1. A suspension insulator for mounting high tension conductors on a supporting member comprising a plurality of securing means connected to said supporting member in vertically spaced relation, a plurality of rigid insulating rod means arranged in V formation, means for pivotally connecting one end of each rod to an adjacent securing means, said insulating rod means being substantially coaxially pivotal about said supporting member on an axis inclined to the vertical and means connected to the opposite ends of said rods for joining said ends, said last named means also supporting a high tension conductor supporting means and being positioned intermediate the vertical limits of said securing means.

2. A suspension insulator for mounting high tension conductors on a supporting member comprising a plurality of securing means connected to said supporting member in vertical spaced relation, a plurality of rigid porcelain insulator rods arranged in converging relationship, means for pivotally connecting one end of each rod to one of said securing means, said insulating rods, being substantially coaxially pivotal about said supporting member on an axis inclined to the vertical rigid means connected to the opposite adjacent ends of the said rods for joining said ends together, said last named means serving to maintain said rods against vertical movement, and means for directly securing a conductor clamp to said last named means.

3. A suspension insulator for mounting high tension conductors on a supporting member comprising a plurality of clevises connected to said supporting member in vertical spaced relation, a plurality of rigid insulator rods arranged in V-relationship with one rod horizontal, a metallic member connected to one end of each rod, said metallic members being adapted to be connected one to each of the said clevises, rigid means for joining the opposite ends of the said insulator rods near each other, said means serving to maintain the adjacent ends of said rods in fixed position and against vertical movement, and a conductor clamp secured to said rigid means for supporting a conductor.

4. A suspension insulator for mounting high tension conductors on a supporting member comprising a plurality of clevis members connected to said supporting member in vertical spaced relation, a plurality of rigid porcelain insulator rods, a cap member secured to one end of each rod, each cap member having a projection adapted to be connected one to each clevis, a metallic member having a plurality of sockets connected thereto, the opposite ends of said insulator rods being adapted respectively to be received one in each socket, means for securing said rods in said sockets, and means for connecting a conductor to said metallic member.

5. A suspension insulator for mounting high

tension conductors on a supporting member comprising means for securing to said supporting member a pair of porcelain insulator rods in vertical spaced relation, rigid means connected to the opposite ends of said rods for connecting said ends adjacent each other, said means serving to maintain said rods in fixed vertical relation, and a conductor pivotally connected to said last named means, one only of said rods being so arranged that the weight of said conductors maintains said rod under compression.

6. A suspension insulator for mounting high tension conductors on a supporting member comprising means for securing to said supporting member a pair of porcelain insulator rods in vertical spaced relation, rigid means connected to the opposite ends of said rods for connecting said ends adjacent each other, said means serving to maintain said rods in fixed vertical relation, and a conductor pivotally connected to said last named means, one only of said rods being so arranged that the weight of said conductors maintains said rod under tension.

7. A suspension insulator for mounting high tension conductors on a supporting member comprising a plurality of securing means connected to said supporting member in vertical spaced relation, a plurality of rigid porcelain insulator rods, means for connecting one end of each rod to one of said securing means, and rigid means joining the opposite ends of said rods together, said last named means serving to maintain said rods against vertical movement, one of said rods being under compression and another of said rods being under tension when in operative position.

8. A suspension insulator for mounting high tension conductors on a supporting member, comprising a plurality of securing means connected to said supporting member in vertical spaced relation, a plurality of rigid porcelain insulator rods, means for connecting one end of each rod to one of said securing means, and means for releasably connecting the opposite ends of said rods, said last named means being arranged to support the transmission conductor, the securing means for connecting said rods to the supporting member being disposed so as to yieldingly maintain said rods at right angles to said transmission conductor.

9. A support for mounting high tension conductors on a supporting member comprising a single insulating rod extending at right angles to the support, said rod being pivotally connected to and pivotal about said support, diagonal means pivotal with said rod for bracing said rod, and means carried by said rod for supporting a plurality of conducting cables in spaced relation.

10. A suspension insulator for mounting high tension conductors on a rigid supporting member comprising a plurality of securing means connected to said supporting member in vertical spaced relation, a plurality of rigid porcelain insulator rods, means for connecting one end of each rod to one of said securing means, means for releasably connecting together the opposite ends of said rods, at least one of said rods carrying a lightning arrester, and means for supporting a high tension conductor adjacent the connected portion of said rods.

11. A suspension insulator for mounting high tension transmission conductors on a rigid supporting member comprising a plurality of porcelain rods each hingably connected at one end to

said support and forming a V arrangement, means spaced from said hinge connections for connecting to each other the opposite ends of said rods, each of said rods being offset outwardly of said support relative to any lower rod so that any movement of said rods from normal position will cause the connected ends of said arms to move in an ascending spiral path, and means carried by said connected ends of said rods for supporting a transmission conductor.

12. A suspension insulator for mounting high tension conductors on a supporting member comprising an insulating rod and means for bracing said rod, said rod and means being connected at one of their ends and having their other ends 15 pivotally attached to said supporting member in vertically spaced relation, and said rod and means being pivotal substantially coaxially about said support on an axis inclined to the vertical.
